US00D440489S

(12) United States Design Patent
Igami et al.

(10) Patent No.: US D440,489 S
(45) Date of Patent:  Apr. 17, 2001

(54) PACKAGE FOR ELECTRONIC DEVICE

(75) Inventors: Hideo Igami, Fujisawa; Yuhta Ishii, Machida, both of (JP)

(73) Assignee: IBM Japan Business Logistics Co., Ltd., Tokyo (JP)

() Term: 14 Years

(21) Appl. No.: 29/122,268

(22) Filed: Apr. 25, 2000

(51) LOC (7) Cl. 09-03

(52) U.S. Cl. D9/426; D9/423

(58) Field of Search D9/420-426, 414, D9/337, 341; D3/273; 206/730, 216, 307, 316.1, 701, 711, 477, 478, 485, 486, 487, 525, 320; 220/4.23, 4.26, 4.21, 836, 376, 266, 784, 835, 839
